UNITED STATES PATENT OFFICE

141,582

DESIGN FOR A SHOE

Jean Margouleff, New York, N. Y.

Application March 14, 1945, Serial No. 118,481

Term of patent 7 years

(Cl. D7—7)

To all whom it may concern:

Be it known that I, Jean Margouleff, a citizen of the United States and a resident of the county of Nassau, city and State of New York, have invented a new, original, and ornamental Design for Shoes, of which the following is a specification, reference being had to the accompanying drawing, forming part thereof, in which:

Fig. 1 is a plan view of a shoe showing my new design.

Fig. 2 is a side elevation of the shoe of Fig. 1.

Fig. 3 is a perspective view of the shoe with the flap portions thereof turned up, observed from the front.

Fig. 4 is a perspective view of the shoe also with the flap portion thereof turned up, observed from the rear.

I claim:

The ornamental design for a shoe, as shown and described.

JEAN MARGOULEFF.
